THREADED STOPPER ATTACHMENT FOR
INTERNAL THREAD LATHE CHUCKS

Jesse A. Darling, Jackson Heights, N. Y.

Application October 1, 1952, Serial No. 312,497

3 Claims. (Cl. 279—1)

1

The present invention relates to improvements in chucks for lathes, especially to improvements in wire chucks for lathes, especially to improvements in wire chucks for small lathes such as watchmaker's lathes, although the principle of the present invention can be applied also to other types of chucks for lathes of any size and the like. More specifically, the present invention relates to new and improved stopper attachments for lathes.

One object of the present invention is the provision of a device of the character described which facilitates the removing of short pieces from the chuck, after they have been placed into the chuck and have been worked on, by ejecting said short pieces by pushing a rod that is slidably extended into the chuck through the device and through the draw-in spindle of the lathe.

Another object of the present invention is the provision of a device of the character described which can be adjusted in such a manner as to limit the depth to which pieces can be inserted into the chuck, so that all pieces resting against the device will extend into the chuck at exactly the same distance. This feature of the present invention also allows removal from the chuck of a piece of stock, during the process of working thereon and then reinserting it into the chuck quickly and easily in the same position in which it was prior to its removal, so that the reinserted piece will run more true in the lathe than it would if reinserted into the chuck at some other position.

A further object of the present invention is the provision of a device of the character described which permits, to hold safely and securely very short pieces in the chuck, because a short piece resting against the device within the chuck not only can be more easily and more quickly inserted therewith, it also will be less apt to be dislocated than if it is held only by the radially engaging jaw portions of the chuck. Moreover, the aforementioned rod greatly facilitates the cutting off of pieces of stock to length.

Yet still another object of the present invention is the provision of a device of the character described which is simple in construction, inexpensive to manufacture, light in weight, simple and handy in use and which can be installed not only in newly manufactured lathes but also in lathes already in use without any substantial alterations of same.

With the foregoing and other objects in view which will appear as the description proceeds, the invention consists of certain novel details of construction and combinations of parts hereinafter more fully described and pointed out in the

2

claims, it being understood that changes may be made in the construction and arrangement of parts without departing from the spirit of the invention as claimed.

5 In the accompanying drawing a preferred form of the invention has been shown.

In said drawing:

Figure 1 is a longitudinal sectional view of a preferred embodiment of my invention on the line 1—1 of Figure 2.

Figure 2 is a cross-sectional view on the line 2—2 of Figure 1, and

10 Figure 3 is a detailed side view of a hollow screw, a tubular member, a sleeve member and lock nuts.

15 Similar reference characters refer to similar parts throughout the several views.

In the drawing (Figure 1) are indicated in dash-and-dotted lines a draw-in spindle 2 of 20 a lathe and a hand wheel 4 provided at one end of the spindle 2. The members 2 and 4 are no parts of my present invention. A chuck 6, which in the instance shown is a wire chuck having a head portion 8, an externally and internally threaded end portion 10, and an axial bore 12, is screwed with its external thread into the draw-in spindle 2 in the usual manner. An internally and externally threaded tubular member 14 is partially screwed into the internally threaded 25 end portion of said chuck in such a manner that a portion thereof protrudes outwardly beyond said end portion 10, and a screw 16 which has a flat, smooth preferably polished head portion 18, a threaded longitudinal shaft portion 20 and 30 a bore 22 extending through its entire length is screwed through said tubular member and extended into the axial bore of said chuck in such a manner, that its head portion is near the head portion of said chuck while the main section of its shaft portion protrudes beyond the threaded 35 end portion of said chuck through the spindle 2 and terminates beyond the end of the spindle 2 and the handwheel 4. A rod 24 extends into the bore 22 and is slidably therein. The rod 24 preferably is provided with a head 26 (Fig. 1) for facilitating its handling and pushing into and pulling out of the bore 22. The rod 24 is somewhat longer than the screw 16, so that it can be extended therethrough entirely for pushing work pieces 40 (not shown) out of the chuck 6. The screw 16 can be screwed more or less deep into the chuck 6, according to the type of work to be carried out. Once the screw 16 has been adjusted to a desired 45 position the head portion 18 will limit the depth at which pieces can be inserted into the chuck 6, and proper inserting of said pieces will be 50 facilitated by pushing the pieces so far into the

55

chuck 6 that they rest against the head portion 18 of the screw 16.

In order to prevent the screw 16 from changing its position during rotation of the chuck 6 I prefer to screw externally knurled lock nuts 28 and 30 upon the tubular member 14 and the shaft portion 20 of the screw 16 adjacent the threaded end portion 10 of the chuck 6 respectively. The shaft portion 20 of the screw 16 being of considerable length, because it extends lengthwise through the spindle 2, it is preferred to prevent a radial swinging thereof during rotation by interposing a sleeve member 32 between the shaft portion 20 and the inner side of the spindle 2, I prefer to make the sleeve member 32 tapered at its ends, as shown, and to provide it with an internal thread, so that it can be screwed upon the shaft portion 20, preferably in such a manner, that it partially protrudes beyond the outer end of the spindle 2 at the hand wheel 4. An externally knurled locknut 34 preferably is screwed upon the outer end of the shaft portion 20 adjacent the member 32 for securing the same.

Since certain changes may be made in the above article and different embodiments of the invention could be made without departing from the scope thereof, it is intended that all matter contained in the above description or shown in the accompanying drawing shall be interpreted as illustrative and not in a limited sense.

It is also to be understood that the following claims are intended to cover all of the generic and specific features of the invention herein described, and all statements of the scope of the invention which as a matter of language might be said to fall therebetween.

Having thus fully described my said invention, what I claim as new and desire to secure by Letters Patent is:

1. In a lathe having a draw-in spindle and a hand wheel provided at one end of said draw-in spindle, a chuck provided with an axial bore and having a head portion as well as an internally and externally threaded end portion and said externally threaded portion being adapted to be screwed into that end of the draw-in spindle which is opposite the end provided with said hand wheel, an internally and externally threaded tubular member being partially screwed into the internally threaded end portion of said chuck in such a manner that a portion thereof protrudes outwardly beyond said end portion of said chuck, a first lock nut screwed upon that portion of said tubular member which protrudes beyond said end portion of said chuck, a screw having a head portion and a threaded shaft portion and being provided with an axial bore being screwed through said tubular member and extended into the axial bore of said chuck in such a manner that its head portion is near the head portion of said chuck while the main section of its shaft portion protrudes beyond the threaded end portion of said chuck through the draw-in spindle of the lathe to which that chuck is attached, a second lock nut adjacent said tubular member being screwed upon the shaft portion of said screw, an internally threaded sleeve member having tapered outer end portions being screwed upon the end section of the shaft portion of said screw, a third lock nut adjacent said sleeve member being screwed upon the shaft portion of said screw, and a rod slidably extending through the axial bore in said screw.

2. In a lathe having a draw-in spindle and a hand wheel provided at one end of said spindle,

a chuck provided with an axial bore and having a head portion as well as an internally and externally threaded end portion and said externally threaded portion being screwed into that end of said spindle which is opposite the end provided with said hand wheel, an internally and externally threaded tubular member being partially screwed into the internally threaded end portion of said chuck in such a manner that a portion thereof protrudes beyond said end portion of said chuck, a first lock nut knurled at its outer side being screwed upon that portion of said tubular member which protrudes beyond said end portion of said chuck, a screw having a head portion and a threaded shaft portion and being provided with an axial bore being screwed through said tubular member and extended into the axial bore of said chuck in such a manner that its head portion is near the head portion of said chuck while the main portion of its shaft protrudes beyond the threaded end portion of said chuck through said draw-in spindle and terminates outside thereof and beyond that end of said spindle which is provided with said hand wheel, a second lock nut knurled at its outer side being adjacent said tubular member screwed upon the shaft portion of said screw, an internally threaded sleeve member being screwed upon that section of the shaft portion of said screw which extends through the end portion of said draw-in spindle that is provided with said hand wheel, a third lock nut knurled at its outer side being adjacent said sleeve member screwed upon the shaft portion of said screw, and a rod slidably extending into the axial bore of said screw from that end thereof upon which is screwed said third lock nut and being longer than said screw.

3. In a lathe having a draw-in spindle and a hand wheel provided at one end of said draw-in spindle, a chuck provided with an axial bore and having a head portion as well as an internally and externally threaded end portion and said externally threaded end portion being constructed and arranged to be screwed into that end of said draw-in spindle which is opposite the end provided with said hand wheel, an internally and externally threaded tubular member being screwed into the internally threaded end portion of said chuck in such a manner that a portion thereof protrudes beyond said end portion of said chuck, a screw having a head portion and a threaded shaft portion and being provided with an axial bore being screwed through said tubular member and extended into the axial bore of said chuck in such a manner that its head portion is near the head portion of said chuck while the main portion of its shaft portion protrudes beyond the threaded end portion of said chuck through the draw-in spindle of the lathe to which said chuck is attached, a rod slidably extended through the axial bore in said screw, means for preventing a radial swinging of the shaft portion of said screw while rotating, and means for preventing an unscrewing of said screw.

JESSE A. DARLING.
